CRACKING PROCESS

Herbert H. Meier, Baytown, Tex., assignor to
 Standard Oil Development Company, a corpora-
 tion of Delaware

Application April 10, 1944, Serial No. 530,366

5 Claims. (Cl. 196—49)

1

The present invention is directed to the thermal treatment of hydrocarbon oils, and more particularly to the cracking of hydrocarbon oils to produce valuable products.

In accordance with the present invention, hydrocarbon oils, such as gas oil obtained from petroleum, are subjected to treatment including catalytic cracking and thermal cracking to produce substantial amounts of valuable components including butylenes, isobutane and aviation grade naphtha. The catalytic cracking step employed in the process of the present invention preferably employs the so-called fluid catalytic cracking technique. This technique is now widely known in industry and may be described briefly as involving the use of a finely divided catalyst which moves along with the oil flowing through the catalytic cracking reaction system. After the catalytic cracking reaction is completed, the finely divided catalyst is separated from the oil, regenerated and subsequently returned to the catalytic cracking zone. The conditions maintained in the catalytic reaction system may be varied in accordance to the charge stocks being treated, but in general the temperatures will be in the range of 850° to 1000° F., with pressures ranging from 10 to 20 pounds per square inch. It is usual to employ an alumina silica catalyst in commercial catalytic cracking units, but other catalysts well known to the catalytic cracking art may be employed if desired. The thermal cracking step employed in the present invention may be carried out by subjecting the oil being reacted to a temperature in the range of 1000° to 1300° F. under a pressure ranging from 50 to 800 pounds per square inch. If desired, steam may be injected into the material being thermally cracked in amounts up to 100 mole per cent, based on the charge.

The period the oil is retained under thermal cracking conditions may be varied over a wide range, with contact times varying from an order of .5 to 5 seconds up to more than 300 seconds.

In its more specific aspects the present invention may be described as involving the catalytic cracking of gas oil, the separation of a fraction in the naphtha boiling range from the product of the catalytic cracking process, the thermal cracking of this fraction, and the subsequent finishing of the thermally cracked fraction to obtain an aviation grade naphtha. When employing this process the product from the catalytic cracking step may be fractionated to obtain substantial amounts of butylenes and isobutanes therefrom,

as well as the naphtha fraction which is subsequently subjected to thermal cracking.

It is an advantage of the present invention that the throughput of the unit wherein the catalytic cracking step takes place may be substantially increased above its normal rating which results in increased amounts of aviation grade naphtha and butylenes and isobutanes for a given capacity of a catalytic cracking unit. An additional advantage of the present invention is that a large amount of stable aviation grade naphtha may be produced with a minimum loss of components charged to the process. Other objects and advantages of the present invention may be seen from the following description taken with the drawing, in which the sole figure is in the form of a flow sheet diagrammatically illustrating a preferred method for conducting the treatment of the present invention.

Turning now to the drawing, a charging stock, such as gas oil, is passed via inlet 11 into catalytic cracking unit 12. Within the cracking unit the gas oil is subjected to suitable thermal conditions in the presence of a catalyst to produce substantial amounts of hydrocarbons in the naphtha boiling range, as well as lighter hydrocarbons, such as butylenes and isobutane. The temperature conditions maintained within cracking unit 12 may be within the range of 800° to 1000° F., in accordance with conventional practice of operating fluid catalyst cracking units, and the other conditions within the unit may also be maintained in accordance with conventional practice. The product from unit 12 may be withdrawn via line 13 and discharged into fractionating column 14. Within fractionating unit 14 the product from the catalytic cracking unit may be divided into a plurality of fractions. A heating coil 15 is provided in the lower end of the unit to aid in the vaporization of the hydrocarbons therein, and the feed into this unit may be divided into a heavy bottoms and withdrawn via outlet 16, and a light fraction consisting principally of butylenes, isobutanes and light naphtha which may be withdrawn as overhead from the top of the tower via line 17. In addition, a selected fraction in the naphtha boiling range may be withdrawn as a side stream from outlet 18 and passed to thermal cracking unit 19. The naphtha fraction withdrawn as a side stream may advantageously have a boiling range of from 200° to 400° F. Column 14 and the streams drawn therefrom are shown diagrammatically in the figure, and it is to be understood that the distillation step may be conducted in a plurality of columns,

and that the naphtha fraction withdrawn for subsequent treatment in the thermal cracking unit may be divided into a number of fractions and each fraction treated by thermal cracking. For example, a naphtha fraction boiling in the range of 200° to 350° F. and another naphtha fraction boiling in the range of 350° to 400° F. may be separately withdrawn from the distillation unit and separately subjected to thermal cracking.

In thermal cracking unit 19 the naphtha fraction may be subjected to a temperature in the range of from 1000° to 1300° F., depending upon the character of the fractions being treated, with pressures ranging from 50 to 800 pounds per square inch. If desired, steam may be injected with the naphtha fraction being cracked in accordance with the well known technique of thermal cracking fractions in the naphtha boiling range. The product from thermal cracking unit 19 is discharged via line 20 into fractionating column 21, provided with heating coil 22.

The material in column 21 may be divided into a heavy fraction withdrawn as bottoms via outlet 23, a medium fraction withdrawn as a side stream via outlet 24, and a light fraction withdrawn as overhead via line 25. It will usually be found desirable to operate distillation tower 21 to separate a side stream having a boiling range approximately that treated in thermal cracking unit 19. If, for example, the naphtha fraction charged to thermal cracking unit 19 had a boiling range of 200° to 400° F., it is desirable to withdraw a fraction of this same boiling range as a side stream via line 24. This side stream fraction is high in aromatic content and is advantageously finished to obtain an aviation grade naphtha. In order to carry out this finishing step, sulfuric acid may be injected into the fraction flowing through line 24 by means of line 10, the two components being admixed in mixer 26 and subsequently discharging through line 26' into settling vessel 27. Acid sludge is withdrawn from the lower portion of vessel 27 by means of outlet 28, and the naphtha fraction is withdrawn from an upper portion of vessel 27 by means of line 29, has added thereto sodium hydroxide by

of 200° to 350° F. as overhead, via line 38, with the remainder withdrawn as bottoms by line 39. The overhead fraction is preferably caustic washed with sodium hydroxide added thereto through inlet 40, the admixture passed to settler 41, where it is allowed to settle into a spent caustic layer and naphtha layer, and the spent caustic layer withdrawn through outlet 48. The naphtha fraction may be withdrawn from settler 41 by means of line 42, and is ready to be used as an aviation naphtha either with or without further blending. It is commercially desirable to blend this stock with various components, and, as shown in the drawing, an inhibitor may be added to the fraction flowing through line 42 by means of inlet 43, an isopentane fraction may be added via line 44, an alkylate fraction via line 45, and an anti-knock agent, such as tetraethyl lead, via line 46. The naphtha fraction with these various addition agents may be discharged into storage 47, and will be a finished high quality aviation grade fuel.

An indication of the high quality of products by the practice of the present invention, as well as the yield, is found in the following table. In obtaining the data set forth therein, 30° A. P. I. gas oil fractions were first subjected to cracking in a fluid catalyst cracking unit at a maximum reactor temperature of 975° F. The product from the fluid catalyst cracking unit was then distilled to separate fractions in the naphtha boiling range and the naphtha fractions then subjected to cracking in the thermal cracking unit at a temperature ranging between 1000° F. and 1030° F. and at a pressure of 750 pounds per square inch. The advantage of subjecting the fractions to the re-cracking in the thermal unit is indicated by the substantial increase in octane number obtained by passing the fraction through the thermal cracking unit. In the table, F. C. C. U. is an abbreviation for "fluid catalytic cracking unit," and T. C. U. is an abbreviation for "thermal cracking unit." It will be seen that the first five runs were carried out using a paraffinic gas oil as the charging stock and runs VI and VII were carried out with a naphthenic gas oil as the charging stock.

Table I

Charge to F. C. C. U.	Paraffinic gas oil					Naphthenic gas oil	
	Run I	Run II	Run III	Run IV	Run V	Run VI	Run VII
Conversion at F. C. C. U. percent	67	67	60	60	60	63.5	63.5
Temperature of T. C. U.	1,010	1,010	1,000	1,015	1,030	1,010	1,010
Yield from T. C. U. percent feed	63.0	16.4	61.5	61.7	55.2	77.2	19.2
Fraction to T. C. U. °F.	205-350	350-400	205-350	205-350	205-350	205-350	350-400
Octane No.:							
Before re-cracking—

Octane No.:							
After re-cracking—							
1-C (A.S.T.M.)	93.2	90.7	95.8	97.4	98.7	99.2	96.7
3-C (AN) I. M. E. P.	131	153	215	226.5	241	181	138

means of inlet line 30, and the two components are then admixed by passing through mixer 31 and discharge into settling vessel 32. Spent sodium hydroxide solution is withdrawn from a lower portion of vessel 32 by means of outlet line 33. A naphtha fraction is withdrawn through line 34 and has alkali solution or soap bottoms added thereto by inlet line 35 and is discharged into fractionating tower 36, provided with heating coil 37. It is preferred to operate distillation tower 36 to remove a fraction boiling in the range 75

It will be noted that runs III, IV and V were processed in the same manner in the fluid catalytic cracking unit, but were thermally treated at temperatures of 1000°, 1015° and 1030° F., respectively, in the thermal cracking unit. It will be observed that the use of the higher temperatures in the thermal catalytic cracking unit produced a higher octane number in the finished product, but lowered the yield.

Because of its large initial investment, it is usually desirable to employ the fluid catalytic

cracking unit to the utmost advantage. It is quite often convenient to determine the value of the output of the fluid catalytic cracking unit by determining the amount per day of aviation grade naphtha and butylenes and isobutanes which may be obtained from its operation. In order to ascertain the optimum rate of operation of the fluid catalytic cracking unit described above, comparative runs were made using different rates of feed. The results of these runs are shown in the following table. The fluid catalytic cracking unit employed had a rated capacity of 13,300 barrels per day at 65% conversion on 30° A. P. I. gas oil. When conducting a series of comparative runs it was found that by lowering the input the per cent conversion obtained was increased, but that by increasing the throughput the amount of converted product measured in barrels per day was increased. The exemplification of these results is set out in the following table, in which run I shows the quality and amount of product obtained from the fluid catalytic cracking unit when operating at a throughput of 10,000 barrels per day, while run II indicates the results obtained with a throughput of 17,600 barrels per day. The product from the fluid catalytic cracking unit was distilled and a naphtha fraction boiling in the range of 205° to 300° F. was then subjected to a thermal cracking operation carried out at 1015° F. The substantial improvement of the product obtained when thermally cracking the naphtha separated from the product of the fluid catalytic cracking unit is evident in the octane numbers of the fractions shown.

Table II

Run	Charge rate to F. C. C. U. B/D	Conversion at F. C. C. U., percent	205-350° F. fraction from F. C. C. U.			205-350° F. fraction from T. C. U.		
			Amt. B/D	Octane No.		Amt. B/D	Octane No.	
				1-C (A. S. T. M.)	3-C (AN) I. M. E. P.		1-C (A. S. T. M.)	3-C (AN) I. M. E. P.
I	10,000	71	1,251	90.6	219	1,005	97.0	260
II	17,600	60	2,153	88.8	185	1,675	95.7	216

Although not shown in the table above, the yield of butylenes and isobutanes on a barrels-per-day basis is also increased by increasing the charge rate of the fluid catalytic cracking unit. The yield of butylenes formed in the fluid catalytic cracking unit decreases from 9.2% to 7.0% as the feed rate is increased from 10,000 to 17,600 barrels per day, but the amount of butylenes obtained increases from 920 barrels to 1,225 barrels per day over the same range. Similarly, the yield of isobutane is decreased from 9.3% to 6.3%, but the amount produced increases from 930 barrels to 1,115 barrels per day as the feed rate is changed from 10,000 to 17,600 barrels per day.

It is postulated that the combination treatment including a preliminary fluid catalytic cracking step followed by a thermal cracking step produces an improved quality product by the forming of large amounts of aromatics in the catalytic cracking step and the decomposition of naphthenic compounds into aromatics in the thermal cracking step. It has been found that the naphthas obtained from the thermal cracking step may be satisfactorily treated with a small amount of sulfuric acid, of the order of 10 pounds of acid per barrel of naphtha, and that the naphtha obtained is stable against gum formation, and of aviation grade. From the data appearing both

in Table I and Table II, it will be evident that naphthas obtained from the fluid catalytic cracking unit which were of marginal grade for aviation fuel have been converted into high quality aviation naphthas. The thermal treatment of the catalytically cracked fractions not only produces high grade aviation naphthas, but in addition allows the catalytic cracking unit to be operated with a very high throughput, with an increased product on a barrels-per-day basis, both of naphtha fractions and also butylene and isobutane fractions. It is to be noted that although the rating of the naphthas subjected to the thermal cracking step is substantially improved, the amount of material lost by this treatment is relatively small.

While I have disclosed specific examples illustrating the practice of the present invention, the conditions set forth in these examples are given by way of illustration only and are not intended as limitations. It will be appreciated that the temperature of operation in the fluid catalytic cracking unit, the charging rate, catalyst used and the temperature of operation in the thermal cracking unit and the charging rate, as well as the steps of finishing the naphtha fraction withdrawn from the thermal cracking unit may be varied substantially without departing from the scope of the present invention, and it is my intention to embrace such changes by the hereto appended claims.

I claim:

1. A method for treating hydrocarbons comprising the steps of charging a petroleum fraction in the gas oil boiling range to a catalytic crack-

ing unit and maintaining it therein at a temperature in the range of 850° to 1000° F. to cause substantial cracking thereof, removing the product resulting from the cracking of the fraction in the gas oil boiling range from the catalytic cracking unit, separating a fraction in the naphtha boiling range therefrom, passing said fraction to a thermal cracking zone maintained in the temperature range of 1000° to 1300° F. to cause cracking thereof, removing product resulting from the cracking of the fraction in the naphtha boiling range from the thermal cracking zone and subjecting said product to distillation conditions in a fractionating zone to separate a naphtha fraction boiling above 200° F. and no higher than 400° F.

2. A method in accordance with claim 1 in which the naphtha separated in the fractionating zone is treated with sulfuric acid to form a finished aviation grade naphtha.

3. A method for treating hydrocarbons comprising the steps of subjecting a petroleum fraction in the gas oil boiling range to cracking conditions in a catalytic cracking zone at a temperature of approximately 950° F., removing the product resulting from the cracking of the fraction in the gas oil boiling range from the catalytic cracking zone and fractionating in a first

fractionating zone to separate a side stream boiling above 200° F. and no higher than 400° F., subjecting said fraction to cracking conditions in a thermal cracking zone maintained in a temperature range of 1000° to 1300° F., removing product resulting from the cracking of the side stream fraction from the thermal cracking zone to a second fractionating zone, separating a naphtha fraction from the second separating zone boiling above 200° and no higher than 400° F. and subjecting said naphtha fraction to finishing treatments to obtain an aviation grade motor fuel.

4. A process in accordance with claim 3 in which the charging rate of gas oil to the catalytic cracking zone is adjusted to obtain a conversion of approximately 60%.
5. A process in accordance with claim 3 in which butylenes and isobutanes are separated from the product from the catalytic cracking zone in the first fractionating step, and in which the gas oil is charged to the catalytic cracking unit at a sufficiently high rate to obtain a conversion therein of approximately 60%.

HERBERT H. MEIER.
